CLAIM

The ornamental design for a checkerboard, as shown and described.

DESCRIPTION

FIG. 1 is a perspective view of a checkerboard in accordance with the present invention;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a perspective view of the checkerboard of FIG. 1, shown with the cover panels in the removed position;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side elevation view thereof; and,

FIG. 14 is a right side elevation view thereof.
